UNITED STATES PATENT OFFICE.

EVAN OWEN WILLIAMS, OF PARKSTONE, ENGLAND, ASSIGNOR TO WILLIAMS FOREIGN PATENTS LIMITED, OF LONDON, ENGLAND.

MODE OF CONSTRUCTING REINFORCED-CONCRETE SHIPS, BARGES, FLOATING STRUCTURES, AND THE LIKE.

1,353,107.

Specification of Letters Patent. Patented Sept. 14, 1920.

Application filed May 15, 1918. Serial No. 234,764.

To all whom it may concern:

Be it known that I, EVAN OWEN WILLIAMS, B. Sc., A. M. I. C. E., a subject of the King of Great Britain, residing at "Shaston," Ardmore Road, Parkstone, Dorsetshire, England, have invented certain new and useful Improvements in the Mode of Constructing Reinforced-Concrete Ships, Barges, Floating Structures, and the like, of which 10 the following is a specification.

This invention relates to a mode of constructing reinforced concrete ships, barges, floating structures and the like whereby the erection of such structures is greatly simplified and accelerated.

Reinforced concrete structures are generally built with the aid of standardized molds of appropriate shape and usually assembled so as to form between them or between them and any falsework or centering employed at the same time the caviated form or negative of the actual reinforced concrete structure or part thereof to be ultimately molded.

Now, this invention consists in the provision of non-collapsible unit-standardized box-shaped molds and of specific accessories likewise standardized for use in conjunction with particular molds so that by 30 the combined use of particular units in a particular manner according to this invention a mode of constructing reinforced concrete ships is established by which most of the defects inherent in the methods hitherto employed are entirely avoided and reinforced concrete structures of the kind referred to may be erected with greater rapidity and reliability than heretofore.

These non-collapsible molds, for greater 40 convenience and according to the purposes for which they are intended are hereinafter referred to as mold boxes, chute boxes, troughs or shutters, and where such molds, as is preferable are constructed of timber or other wearing material metal bushes are, if necessary employed in all or any holes therein to counteract wear and for the same purposes the exposed surfaces may be lined with a sheathing of thin sheet metal to 50 protect the material from disintegration caused by the concrete.

The characteristics of this invention will now be more fully described with reference to the accompanying drawings illustrating

by way of example some specific forms of 55 mold boxes and the method of their application in the construction of different parts of reinforced concrete structures.

Figure 1 represents in horizontal section in connection with the construction of the 60 bottom of a ship with transverse and longitudinal stiffening ribs thereon mold and chute boxes and other accessories employed according to this invention.

Fig. 2 shows in a similar section the use 65 of superposed or sectional mold boxes and the chute boxes employed in conjunction therewith.

Fig. 3 is a plan of Fig. 2 to a reduced scale showing the chute boxes in position 70 on the mold boxes.

Fig. 4 is a cross section of the transverse bottom ribs showing the manner of molding the inner slab for the double bottom on the top of the ribs. 75

Fig. 5 is a similar view of Fig. 4 showing an alternative method of supporting slabs on the top of the ribs.

Fig. 6 is a vertical section of a single skin wall and deck of a ship and the troughs 80 and other accessories employed for its construction.

Fig. 7 is a longitudinal section of this wall on the line VII—VII of Fig. 6.

Fig. 8 is an inside view of Fig. 6. 85

As shown in Figs. 1 to 5, in order to construct the bottom slab 16 of a ship and the transverse and longitudinal stiffening ribs 17 thereon, blocks, 18, preferably of timber are wedged up by wedges 19 on appropriate supports 20. Troughs or molds 21 of timber or any suitable material are then slipped in from the side of the boat in the recesses formed in the blocks 18 and wedged up by the wedges 22 until the correct alignment of the 95 upper surfaces of the troughs is obtained. For the purpose of attaching the troughs 21 to the blocks 18 coach screws 23 or the like may be employed. The length of the troughs 21 is measured in the direction of 100 the distance between adjacent keel blocks 20 and the width of these troughs so chosen as to make the total weight of a trough unit convenient for handling. When all the bottom troughs are in position the slab 16 is 105 cast thereon and after a suitable period has elapsed, the troughs 21 are removed by releasing the coach screws 23 and the wedges

when the troughs will drop on to the shoulders of the blocks 18, 18 and can be slid out to the side of the boat. This enables the main part of the centering in the bottom of a ship 5 to be readily removed in complete units. Moreover, these bottom troughs can thus be removed in the minimum time with the advantage that any minor defects in the surface of the bottom slab may be remedied 10 before the concrete is in its final hardened state.

After the bottom slab 16 has been cast and formed, mold boxes 24 are placed in position on the top of the slab 16 and maintained 15 at their correct distance one from the other by stiffening blocks 25 and bolts 26.

As shown, each mold box 24 consisting either of wood or metal or other suitable material has its top and bottom left open. The 20 sides preferably taper to inward from the top to the bottom so that when the mold boxes are placed correctly on the bottom slab they resemble frustum of pyramids with the larger ends uppermost. These 25 mold boxes are placed on the bottom slab and arranged in rows transversely and longitudinally in a cellular fashion so that the spaces formed between them represent, in fact, the ultimate shape of the ribs to be 30 cast. Each mold box is provided at the top with an inner projecting lip or flange 27 adapted to support the chute box 28. Each chute box 28 consists preferably of four inclined surfaces and is truncated by 35 a flat top as shown on which the workmen stand when punning the concrete in the ribs 17. Where the ribs 17 are fairly deep it is preferable to form the mold boxes 24 in two or more sections as shown in Fig. 2. 40 In this case the chute boxes 28 are first placed on the lips 27 of the lower sections and when the concrete has reached the top of these lower sections the chute boxes 28 are lifted and the next or upper section of the 45 mold box 24 is placed in position on the last and connected in alinement therewith by the spigot joints 29'. The chute box 28 is then placed on the projections 27 of the upper section 24 and the concrete carried on 50 to the top of the latter. The cellular arrangement of these mold and chute boxes will be readily understood from the illustration shown in Fig. 3.

For the purpose of producing a double 55 bottom and to form the upper slab or inner skin thereof reinforced concrete slabs 29 which have been previously cast are spanned between the tops of the ribs 17. These slabs 29 bear on the ribs 17 as shown at 60 30 in Fig. 4, and when the reinforcement has been placed in position on top of the slabs 29 the inner bottom slab 16' is molded or cast thereon. The previously molded slabs 29, therefore, form in this case the centering to support the top slab 16' while it

is being cast and they also insure that the reinforcement shall have a covering of concrete at least equal to the thickness of the slabs 29.

In Fig. 5 the slabs 29 are shown supported 70 on projections 17' specially formed or molded on the ribs 17.

In constructing a vertical wall of a single slab 2' an outer centering 31 may be employed as hitherto for the outer surface 75 thereof, as shown in Fig. 6. 32 is the horizontal stiffener or rib on the inner surface, and 33 shown in Figs. 7 and 8, are the vertical stiffening ribs to be formed thereon. To form the inner surface and the horizontal 80 and vertical stiffening ribs, troughs or forms 34 are employed in superposition. These troughs have one vertical or upright side open. The vertical or upright side opposite the open side is employed to mold or 85 form the interior surface of the wall slab, the two other vertical or upright sides mold or form the sides of the vertical concrete stiffening ribs and the two horizontal sides are flanges whereby vertical adjacent 90 troughs may be connected one with the other.

The sides of the troughs or forms forming the sides of the vertical concrete ribs are tapered as shown in Fig. 7 so that the 95 horizontal widths of the troughs are greater at the open sides than at the opposite closed sides. These troughs are placed one above the other and preferably bolted together by vertical bolts 35. In a horizontal sense 100 they are held apart by spacing blocks 36 and held together by screw bolts 37. To form the inner faces of the ribs 33 a vertical strip or board 38 is attached to the troughs 34 by screws or other known means. 105 To form the faces on the horizontal stiffening ribs 32 a horizontal strip or board 39 is fitted between the strips 38 and the concrete is continued until the strip 39 is reached. The next unit 34 is then placed directly on 110 top of the concrete rib 32 and connected through the latter by a bolt 40 to the lower unit 34 as shown. In this way the vertical wall is gradually built up and in order 115 then to form the deck slab 1 projecting from the side of the ship, special unit troughs 41 shaped for the particular purpose are employed. These troughs 41 are placed in 120 position on top of the uppermost troughs 34 and the end of each trough 41 is properly 125 supported by a strut 42. Each trough 41 is preferably connected by a bolt 43 to the centering 31 of the outer surface of the slab 2', the bolts 43 being preferably above the water line.

What I claim and desire to protect by Letters Patent is:—

1. In combination with the bottom slabs of a concrete construction upwardly flaring box shaped molds resembling frustums of 130

pyramids open at top and bottom, said molds being provided with inwardly extending lips and spigot joints for engaging one with the other so that when assembled, 5 their outer walls form the spaces between them to receive concrete to provide stiffening ribs on said bottom slab, substantially as described.

2. In combination with box shaped molds 10 tapered upwardly and open at top and bottom, said molds being arranged with spaces between them to receive concrete, and chute boxes having downwardly and outwardly

inclined surfaces seated on the mold boxes, and having flat tops, said chute boxes covering the interior of the mold boxes and directing the material to the rib forming spaces between them and being interchangeable in respect to molds. 15

In testimony whereof I have affixed my 20 signature in presence of two witnesses.

EVAN OWEN WILLIAMS.
